United States Patent Office.

L. PORTER, OF ROCHESTER, NEW YORK.

Design No. 3,486, dated May 11, 1869.

DESIGN FOR A SEWING-MACHINE FRAME.

The Schedule referred to in these Letters Patent and making part of the same.

To all whom it may concern:

Be it known that I, L. PORTER, of the city of Rochester, in the county of Monroe, and State of New York, have invented or produced a new and original Design for Sewing-Machine Frames; and I do hereby declare that the following is a full, clear, and exact description of the same, referring to the accompanying drawing, making part of this specification, in which the figure represents a side elevation.

This invention is intended to present a pleasing and graceful form of the right-angled standard and supporting-arm, with which the operating parts of the machine are connected, the whole as hereinafter set forth.

In the drawing—

A represents the base;

B, the standard; and

C, the supporting-arm.

The standard and arm, instead of being made of single bars, as in ordinary sewing-machine frames, have each two branching sides, *a a* and *b b*, with an enclosed space, as shown, the object of which is to present a pleasing and graceful appearance to the eye, at the same time that the upper one allows the insertion of the cam-shaft between the sides.

The upper and lower sections of *a a* are formed in graceful curves, *c c*, with intermediate scrolls, *d d*, turning inward, as shown.

At the top angle is also made a pendant, *f*, and at the junction of the standard and arm is formed a pendant scroll, *g*.

The sides *b b* of the horizontal arm are made straight, but slightly converging toward the needle-bar bearing *i*.

Near the base of this arm the inner surfaces are provided with ornamental scrolls, *h h h h*, as clearly shown.

The effect of the standard and arm, formed with the separated sides *a a*, *b b*, and ornamented as described, is pleasing to the eye, and the construction secures additional strength.

Bearings *i*, *k*, *l*, *m*, *n*, *o*, and *p*, are formed for the attachment, respectively, of the needle-bar and presser, the tension, the thread-spool, the cam-shaft, the driving-shaft, and the cloth-plate.

What I claim as my invention, and desire to secure by Letters Patent, is—

The design for sewing-machine frames herein set forth.

In witness whereof, I have hereunto signed my name, in the presence of two subscribing witnesses.

L. PORTER.
